5,271,187 12/1993 Yoneda et al. 451/5

Primary Examiner—Antoine Duval Davis
Attorney, Agent, or Firm—Olson & Hierl, Ltd.[57] **CLAIM**

The ornamental design for a computer numerical control operated tool grinder enclosure, as shown and described.

DESCRIPTION

FIG. 1 is a perspective view of a computer numerical control operated tool grinder enclosure;

FIG. 2 is a front elevational view of a computer numerical control operated tool grinder enclosure;

FIG. 3 is a rear elevational view of a computer numerical control operated tool grinder enclosure;

FIG. 4 is a side elevational view of a computer numerical control operated tool grinder enclosure;

FIG. 5 is an opposite side elevational view of a computer numerical control operated tool grinder enclosure; and,

FIG. 6 is a top plan view thereof.

The broken line showing is for illustrative purposes only and forms no part of the claimed design.
